INTERNAL-COMBUSTION MOTOR.

1,247,982.

Specification of Letters Patent. Patented Nov. 27, 1917.

Application filed January 11, 1915. Serial No. 1,491.

To all whom it may concern:

Be it known that I, DANIEL MEDANICH, a citizen of the United States, and a resident of Buechel, county of Jefferson, and State 5 of Kentucky, have invented a certain new and useful Improvement in Internal-Combustion Motors, of which the following is a specification.

This invention has reference to internal 10 combustion motors and relates especially to improved means of delivering motive fluid to the working cylinder dispensing with the usual carburetor.

A further object is the provision of means 15 for varying the amount of motive fluid delivered.

The invention may be understood from a consideration of the following detailed description, taken in connection with the accompanying drawing, which forms a part of 20 this specification, with the understanding, however, that while the drawing shows a practical embodiment of the invention, the latter by no means limits me to any exact 25 conformity therewith but may be embodied in any other forms which come within the scope of the claims appended hereunto.

In the drawing wherein similar reference 30 characters designate like parts; Figure 1, is a transverse sectional view of a portion of a motor with parts in elevation; Fig. 2, a side elevation of the portion shown in Fig. 1; Fig. 3, a modification of the pump actuating means; Fig. 4, an elevation, partly 35 in section of the spray head; Fig. 5, a view showing the application of a centrifugal governor to control the stroke of the fluid delivery pump.

Referring to the drawing—1—designates 40 a cylinder within which a piston—2—of the usual construction operates. A suitable valve casing—3—, having communication with an inlet port—4—, is fitted in the cylinder head. The casing 3, is provided on 45 its lower end with a valve seat—5—on which a valve—6—closes, an elongated stem—7—extends upward from the valve, passes through the center of the casing, and has an annular collar—8—near its upper 50 end. A coil spring—9—confined between the collar and the casing serves to close the valve 6. The valve is operated by means of a rocker arm—10—pivotally supported centrally at the upper end of a standard 55—11—. To the outer end of the rocker arm

a rod—12—is pivotally connected and depends to engagement with suitable operating means such as a cam—13—secured on a shaft—14—. A valve chest—15—having an exhaust outlet—16—in the upper 60 end thereof is formed with an internal annular seat—17—against which a piston valve—18—closes, and communicates with the cylinder 1 by means of a channel—19—. A rod—20—depends from the valve 18 to 65 engagement with suitable operating means, such as a cam—21—secured on a shaft—22—. An exhaust tube, or pipe,—23—extends from the outlet 16 through the inlet port 4 and is provided on its outer end with 70 suitable connecting means, such as a flange—24—. On the outer end of the inlet port 4 there is secured an air inlet valve—25— which comprises a casing—26—having an opening—27—in its outer end, a bridge 75 bar—28—spanning said opening, a valve stem—29—passing centrally through said bar, a valve head—30—on the inner end of said stem adapted to close the opening 27, an adjusting nut—31—on the outer 80 end of the stem, and a coil spring—32—confined between the nut and the bar which serves to close the valve head on the opening 27. A pump—35—, preferably of the diaphragm variety, suitably positioned for 85 actuation by the motor serves to deliver fuel thereto. A supply pipe—36—leads from a suitable source of fuel supply to an inlet—37—of the pump. A delivery pipe—39—leads from an outlet—38—of the 90 pump to a three way valve—40—. From the valve 40, the delivery pipe branches, one branch—42—terminating within the inlet port 4 where it is provided with a spray head—43—. A spray head of any 95 suitable construction may be employed, as illustrated it comprises a shield, or abutment,—44—disposed on the end of the pipe, opposite the outlet therefrom, at such an angle that the fluid from the pipe will impinge thereon and be nebulized and deflected thereby. The spray head is so positioned that the spray therefrom will strike against the exhaust pipe 23 and be vaporized by the heat thereof. The other branch 100—45—of the delivery pipe leads from the valve 40 to a connection with a spray plug—46—inserted in the side of the cylinder in such a position that the spray therefrom 105 will be directed on the head of the piston. 110

The spray plug may be arranged in the side of the cylinder at any suitable point and in any suitable manner. As illustrated it comprises a screw threaded plug having a conical recess —48— in its inner face, a duct —49— extended from the side of the plug and opening into said recess and a passage —50— running from the outer face of the plug to a connection with the duct 49, the 5 delivering pipe 45 being connected in the passage 50. The pump 35 comprises a substantially cup shaped body portion —51— within which, on an annular ledge —53—, a diaphragm —54— is clamped by means 10 of a screw threaded retaining ring —55—. A striker pin —56— is centrally positioned on the diaphragm to receive the impulses from the operating mechanism. The pump is secured by suitable means on a plate, or bar 15 —57—. A transmission element —60— is provided which comprises upper and lower arms —62, 63— arranged in angular relationship on and extending in parallel contiguous planes from one side of a shaft 20 —61—, and a coil spring —66— interposed between the outer ends of said arms; the upper arm 62 being rigidly secured to the shaft 61 and the lower arm being free to turn relative thereto. The transmission element 25 —60— is so positioned on the shaft 61, relative to the pump 35 that the outer end of the lower arm will rest on the pin 56 in the center of the diaphragm. On the proximate sides of the arms, at the outer ends 30 thereof are lateral projections —64, 65— which lie in parallel horizontal planes and in vertical alinement. The lower end of the coil spring 66, fits about a stud —67— on the lower arm 62 and the upper end thereof 35 —68— which depends from the upper arm 63, the spring 66 serves to space the arms apart and after sustaining a certain amount of compression to transmit motion from the upper to the lower arm. 40 The tension of the spring and consequently the power which may be transmitted thereby may be regulated by means of a nut —69— on the pin —68—. The pump may be operated by any suitable means, that 45 which I have illustrated comprising a cam —59— secured on the shaft 22 in position to impinge upon, and depress the transmission element 60 and through it to the pump. A wedge shaped member —72— is adapted 50 to be interposed between the cam 59 and the upper arm 62 of the transmission element, the arrangement being such that the distance through which the arm 63 and consequently the entire element and the diaphragm of the pump will be depressed by 55 the cam, may be varied by adjusting the wedge to and fro, the broader the portion is which lies between the cam and the arm the greater the distance the diaphragm of the 60 pump will be depressed. The wedge is piv- 65

otally connected at its larger, or rear, end to an arm —73— which is in turn secured on a shaft —74— which may be extended to any convenient point, and means such as a handle —75— attached thereto for turning the shaft in order to adjust the wedge 70 72. The shaft 61 may be extended to a convenient point and provided with means, such as a handle —76—, by which it may be turned and with it the attached arm 62, 75 whereby through the medium of the spring 66 and loose arm 63, the pump may be operated manually in order to prime the motor to start it. The stem 41 of the three way valve 40 may likewise be extended to 80 a convenient point for manipulation.

The operation of the pump may now be understood. The three way valve 40 is turned into position to establish communication between the delivery pipe 39 and the 85 branch 42. The motor is then "turned over" that is, turned manually. As the piston commences its suction stroke the inlet valve 6 is opened, by the action of the cam 13, and a current of air is drawn through the 90 valve 25 and port 4; as the valve 6 opens the cam 59 actuates the pump to force motive agent through the pipes 39 and 42 and spray the same into the current of air, which is entering through the valve 25 by which it 95 is taken up forming a combustible mixture which is compressed and exploded in the working chamber of the motor in the usual manner, the usual recurring cycle then issues. The passage of the burnt products of 100 combustion through the pipe 23 will raise the temperature thereof to a point which will heat the air passing through the port 4 and vaporize a portion of the fuel sprayed thereon, this will result in an intimate mixture and consequently increased efficiency of the motor. When more power is desired, the valve 40 may be turned to direct the motive agent through the branch pipe 45 to the spray plug 46, where it is sprayed direct 105 on the highly heated head of the piston, with the results that it is instantly and completely vaporized and mixes with the heated air being drawn through the port 4. In Fig. 3, a modification of the transmission element is illustrated, wherein, instead of having tight and loose arms mounted on the shaft 61 with a coil spring interposed between the extremities thereof, resilient strips —80, 81— are secured on a lug —82— 110 extending from a collar —83— which is secured on a bracket —84—. The regulating wedge 72, being attached to the upright arm —85— of a lever mounted in a bracket —86—. The arrangement illustrated in 115 Figs. 1 and 2 is more particularly adapted to automobile service, the shafts 61 and 74 and the valve stem 41 being extended to points convenient for manual manipulation, 120 in order to make adjustments in accordance 125 130

with demands on the motor due to exigencies of the road. The arrangement illustrated in Fig. 3, is more particularly applicable to stationary motors. With stationary motors there is no attendant to regulate the delivery of fuel to the motor in accordance with the load and consequently I propose to use a governor to vary the position of the wedge 72, which controls the amount of fuel delivered to the motor. Any suitable style of governor may be employed, that illustrated being of the well known centrifugal type comprising weights —90— mounted at the pivotal connection to a revoluble plate —93— mounted on a support —94—; the upper arm 92 being pivotally secured to a collar —95— which in turn is secured on a revoluble spindle —96— which extends down through the support 94 and rests on an arm —87— of the lever which actuates the regulating wedge. The spindle 96 is driven by a connection leading from a pulley —97— to the motor. Suitable means such as a spring —98— are employed to maintain the parts in their normal position; with the broad portion of the throttle wedge 72 interposed between the actuating cam 59 and the upper member of the transmission element. As the speed of the motor increases the weights 90 will be thrown out from the center drawing the spindle 96 down, which will depress the arm 87 withdrawing the wedge 72 and as a narrower portion of the wedge will be below the cam 59 it will not so soon impart motion to the pump and consequently a less amount of motive agent will be delivered to the motor.

It will be observed that this provides a ready and positive means of controlling the speed of the motor making it responsive to varying demands.

It is thought from the foregoing description of my invention that anyone skilled in the art pertaining thereto may make and use the same.

I claim:

1. In an internal combustion motor, a motor cylinder provided with an inlet valve and having an air passage leading thereto across the head of the cylinder, an exhaust valve, 50 an exhaust pipe leading through said air passage, a pump for delivering motive fluid, a three way cock, a pipe leading from said pump to said cock, a spray plug in the side of the cylinder, a spray plug within the air 55 passage, adapted to direct motive fluid against the exhaust pipe therein and branch pipes leading respectively from said spray plugs to said cock.

2. In an internal combustion motor, a motor cylinder, provided with an inlet valve and having an air passage leading thereto cross the head of the cylinder, an exhaust valve, an exhaust pipe leading through said air passage, a spring controlled inlet valve 60 at the outer end of said air passage, a pump, a delivery pipe leading from said pump and terminating within the air passage in a spray head adapted to direct motive fluid against said exhaust pipe.
